UNITED STATES PATENT OFFICE.

GEORGE P. WIGGINTON, OF KALAMAZOO, MICHIGAN, ASSIGNOR TO KALAMAZOO LOOSE
LEAF BINDER CO., OF KALAMAZOO, MICHIGAN.

TEMPORARY BINDER OR LOOSE-SHEET HOLDER.

1,114,833.

Specification of Letters Patent.

Patented Oct. 27, 1914.

Original application filed September 22, 1913, Serial No. 791,180. Divided and this application filed January 23, 1914. Serial No. 813,866.

To all whom it may concern:

Be it known that I, GEORGE P. WIGGINTON,
a citizen of the United States, residing at
Kalamazoo, Michigan, have invented cer-
5 tain new and useful Improvements in Tem-
porary Binders or Loose-Sheet Holders, of
which the following is a specification.

This invention relates to improvements in temporary binders or loose sheet holders.

10 My improvements relate particularly to the adjusting mechanism.

15 Although capable of embodiment in various structures, I have especially designed my improvements for use in temporary binders or loose sheet holders of the type in which binding strips extend between the covers, such as is shown in United States Letters Patent to Bushong No. 851,276, issued April 23, 1907, this application being 20 a division of my application filed September 22, 1913, Ser. No. 791,180.

The main objects of this invention are:
First, to provide in a temporary binder or
loose sheet holder an improved adjusting
mechanism. Second, to provide in a tem-
25 porary binder or loose sheet holder an im-
proved adjusting mechanism which may be
adjusted either from the inner or outer sides
of the cover containing the adjusting mech-
30 anism. Third, to provide an improved tem-
porary binder which is simple and econom-
ical in structure and simple in adjustment.

Further objects, and objects relating to structural details, will definitely appear from the detailed description to follow.

I accomplish the objects of my invention by the devices and means described in the following specification.

The invention is clearly defined and 40 pointed out in the claims.

A structure which is a preferred embodiment of my invention is clearly illustrated in the accompanying drawing forming a part of this specification, in which:

45 Figure I is a detail outside view of a structure embodying the features of my invention with the covers extended, the outer walls of the covers being omitted. Fig. II is a detail section on a line corresponding to line 2-2 of Fig. I, showing details of the adjusting mechanism. Fig. III is a detail section on a line corresponding to line 3-3 of Fig. I, showing further details of the adjusting mechanism. Fig. IV is a detail sec-

tion on a line corresponding to line 4-4 of 55 Fig. I.

In the drawing similar reference characters refer to similar parts throughout the several views, and the sectional views are taken looking in the direction of the little arrows at the ends of the section lines.

Referring to the drawing, the covers are designated by the numerals 1 and 2. These covers preferably consist of rectangular frames 3 having inner walls 4 and outer walls 5 secured thereto to provide cover chambers or recesses to receive the adjusting mechanism. The frames are preferably of wood and the walls of sheet metal. The outer walls are faced with a suitable binding 70 as 6, while the inner walls are usually faced with paper or other suitable covering 7.

The structure illustrated is provided with clamping bars 8 pivotally mounted on hinge members 9 projecting from the ends of the 75 covers. These clamping or binding bars, however, form no part of my present invention and are, therefore, not described in detail herein.

The binding strips 10 extend between the 80 covers and are connected to cover 2 at 11. The other ends of the binding strips are connected to the adjustable member or cross bar 12 at 13. The adjustable member 12 is guided by the roller 14 which travels in the 85 guide ways 15 on the inner wall 4 of the cover. The adjusting lever 16 is journaled at 17 in the inner and outer cover walls and connected to the adjustable member 12 by means of the link 18 which engages the 90 pivot 19 for the roller 14. The lever 16 is provided with a ratchet 20 with which the pawl 21 coacts. The pawl 21 is pivoted at 22 on the inner wall of the cover and is held 95 yieldingly in or out of engagement with the ratchet by means of the spring 23. This spring is U-shaped and is secured by one arm to the end piece of the cover frame and its other end engages the pawl so that it swings past the center of the pivot as the 100 pawl is rocked to and from engaging position, so that the spring performs the double purpose or function. The end of the pawl 21 is turned laterally through a slot 25 in the cover to provide a finger piece 105 24 whereby the pawl may be engaged or disengaged. The pivot 17 of the lever is provided with a key opening 26 adapted to re-

ceive a key at both sides so that the lever may be adjusted from the inner or the outer sides of the cover. By this construction the binding strips are released by disengaging the pawl, thus affording a quick opening device, that is, one in which the mechanism is released by disengagement of the pawl so that the binding strips may be fully extended. The binding strips may also be 10 quickly retracted.

My improved temporary binder or loose sheet holder is simple and economical in its parts and they are easily assembled.

Having thus described my invention, what 15 I claim as new and desire to secure by Letters Patent, is:

1. The combination with the covers, one of said covers comprising a frame with outer and inner walls providing a chamber therein, binding strips extending between said covers, an adjustable member to which said binding strips are connected, arranged in said cover chamber, the other ends of said binding strips being connected to the other 25 cover, guide pieces secured to the inner wall of the chambered cover, a guide roller on said adjustable member coacting therewith, a pivoted lever journaled on the inner and outer walls of said cover, said lever being 30 provided with a curved ratchet, a link connecting said lever to said adjustable member, a pawl pivotally mounted on the inner wall of the chamber to coact with said curved ratchet on said lever, and a spring 35 adapted to hold said pawl yieldingly in engagement with said ratchet or in its disengaged position, said pawl being provided with a finger piece projecting through a slot in the inner wall.

40 2. The combination with the covers, one of said covers having a chamber therein, binding strips extending between said covers, an adjustable member to which said binding strips are connected, arranged in 45 said cover chamber, the other ends of said binding strips being connected to the other cover, a guide for said adjustable member, a pivoted lever having a ratchet thereon, a link connecting said lever to said ratchet, the pivot of said lever being adapted to receive a key, a pawl coacting with said ratchet on said lever, and means for holding 50 said pawl yieldingly in engagement with said ratchet or out of engagement therewith.

55 3. The combination with the covers, one of said covers having a chamber therein, binding strips extending between said covers, an adjustable member to which said binding strips are connected, arranged in 60 said cover chamber, the other ends of said binding strips being connected to the other cover, a pivoted lever operatively connected to said adjustable member and having a ratchet thereon, a pawl coacting with said 65 ratchet on said lever, means for holding said

pawl yieldingly in engagement with said ratchet or out of engagement therewith.

4. The combination with the covers, one of said covers having a chamber therein, binding strips extending between said covers, an adjustable member to which said binding strips are connected, arranged in said cover chamber, the other ends of said binding strips being connected to the other cover, a pivoted lever operatively connected to said adjustable member and having a ratchet thereon, a pawl coacting with said ratchet on said lever, said pawl being disengageable to release said lever.

5. The combination with the covers, one of said covers comprising a frame with outer and inner walls providing a chamber therein, binding strips extending between said covers, an adjustable member to which said binding strips are connected, arranged in said cover chamber, the other ends of said binding strips being connected to the other cover, a pivoted actuating lever operatively connected to said adjustable member, a pawl pivotally mounted on the inner wall of the chamber to coact with said curved ratchet on said lever, and a spring adapted to hold 90 said pawl yieldingly in engagement with said ratchet or in its disengaged position, said pawl being provided with a finger piece projecting through a slot in the inner wall.

6. The combination with the covers, one of said covers having a chamber therein, binding strips extending between said covers, an adjustable member to which said binding strips are connected arranged in said chamber, the other ends of said binding strips being connected to the other cover, a pivoted adjusting lever for said adjusting member, the pivot of said lever being adapted to receive a key presented from either side of the cover, a means for retaining said lever in its adjusted position.

7. The combination with the covers, one of said covers having a chamber therein, binding strips extending between said covers, an adjustable member to which said binding strips are connected arranged in said chamber, the other ends of said binding strips being connected to the other cover, a pivoted adjusting lever for said adjusting member, the pivot of said lever being adapted to receive a key, a means for retaining said lever in its adjusted position.

8. The combination with the covers, binding strips extending between the covers and connected to one of them, an adjustable member to which said binding strips are connected carried by the other cover, a pivoted lever for adjusting said adjustable member provided with a ratchet, a pawl coacting with said ratchet on said lever, and means for holding said pawl yieldingly into or out of engagement with said ratchet.

9. The combination with the covers, bind-

ing strips extending between the covers and connected to one of them, an adjustable member to which said binding strips are connected carried by the other cover, a pivoted lever for adjusting said adjustable member provided with a ratchet, and a pawl coacting with said ratchet on said lever.

10. The combination with the covers, one of said covers having a chamber therein, binding strips extending between the covers and connected to one of them, an adjustable member to which said binding strips are connected carried by the other cover, a pivoted lever for adjusting said adjustable member, said lever being adapted to be engaged by an operating key.

11. The combination with the covers, one of said covers having a chamber therein, binding strips extending between said covers, an adjustable member to which said binding strips are connected arranged in said cover chamber, the other ends of the binding strips being connected to the other cover; a guide secured to the wall of the chambered cover, a guide on said adjustable member coacting therewith, a pivoted adjusting lever, and a link connecting said lever to said adjustable member.

12. The combination with the covers, binding strips extending between said covers, an adjustable member to which said binding strips are connected, a guide for said adjustable member, a pivoted adjusting lever, a link connecting said lever to said adjustable member, and a pawl and ratchet means for retaining said lever in its adjusted positions.

13. The combination with the covers,

binding strips extending between said covers, an adjustable member to which said binding strips are connected, a guide for said adjustable member, a pivoted adjusting lever connected to said adjustable member, and a pawl and ratchet means for retaining said lever in its adjusted positions.

14. The combination with the covers, one of said covers having a chamber therein, binding strips extending between said covers, an adjustable member to which said binding strips are connected arranged in said cover chamber, the other ends of the binding strips being connected to the other cover, a pivoted lever connected to said adjustable member, said lever being adapted to be operated from the side of the cover by means of a key, and means for retaining said lever in its adjusted positions.

15. The combination with the covers, one of said covers having a chamber therein, binding strips extending between said covers, an adjustable member to which said binding strips are connected arranged in said cover chamber, the other ends of the binding strips being connected to the other cover, a pivoted lever connected to said adjustable member, said lever being adapted to be operated by means of a key, and a pawl and ratchet means for retaining said lever in its adjusted positions.

In witness whereof, I have hereunto set my hand and seal in the presence of two witnesses.

GEORGE P. WIGGINTON. [L.S.]
